UNITED STATES PATENT OFFICE.

CHARLEY HIPPYMAN, OF KUHNS CROSSING, COLORADO.

TRAIN-STOPPING APPARATUS.

1,169,034.

Specification of Letters Patent. Patented Jan. 18, 1916.

Application filed May 4, 1915. Serial No. 25,757.

To all whom it may concern:

Be it known that I, CHARLEY HIPPYMAN, a citizen of the United States of America, residing at Kuhns Crossing, in the State of Colorado, have invented new and useful Improvements in Train-Stopping Apparatus, of which the following is a specification.

This invention relates to improvements in automatic train stopping apparatus and has 10 particular application to a track obstacle.

In carrying out the present invention, it is my purpose to provide a track obstacle which may be associated with a road signal and which will be capable of operation to 15 active position when the road signal blade moves to danger position and which may be rendered inactive when the road signal blade designates clear.

It is also my purpose to improve and simplify the general construction of track obstacles and to provide an obstacle which may be installed and maintained at comparatively small cost, which will operate efficiently and effectively for its intended purpose and wherein the component parts will 25 be so arranged and correlated as to reduce the possibility of derangement to a minimum.

With the above and other objects in view, 30 the invention consists in the construction, combination and arrangement of parts hereinafter set forth in and falling within the scope of the claims.

In the accompanying drawings: Figure 1 35 is a view in side elevation of my improved track obstacle. Fig. 2 is a vertical sectional view through the same, parts being shown in elevation. Fig. 3 is a cross sectional view on the line 5-5 of Fig. 1. Fig. 4 is a like 40 view on the line 6-6 of Fig. 1. Fig. 5 is a diagrammatic view showing the circuit connections of the track obstacle and the circuit connections for the motor carried on the train.

45 In accordance with my present invention, track obstacles are disposed along the trackway and spaced apart appropriate distances and, if desired, these track obstacles may be arranged adjacent to the respective road signals and controlled therefrom. Each track obstacle comprises a base 15 constructed of any suitable material and appropriately fastened to the road bed and disposed adjacent to one side of the trackway. Secured 50 to the upper surface of the base 15 centrally thereof and upstanding therefrom is a pivot

rod 16 and rotatably mounted upon the pivot rod 16 is a vertical post or standard 17 capable of rotary movement in one direction or the other. Suitably secured to the upper 60 surface of the base 15 at diametrically opposite sides of the post 17 are pairs of contacts 18, 19 and fastened to the post 17 and radiating therefrom is an arm 20 having the outer end thereof equipped with a pair 65 of contacts 21 spaced apart and adapted to engage the contacts of either pair 18, 19, according to the direction of rotation of the post 17. Secured to the post 17 adjacent to the upper end thereof are outwardly projecting arms 22 spaced apart vertically and disposed in parallelism with each other. In the present instance, each arm 22 comprises telescopic sections 23 and 24, the section 23 having one end connected to the post 17 and 70 the opposite end slidably receiving one end portion of the section 24. Mounted within the section 24 is a coiled expansion spring 25 having one end abutting the end wall of the section 24 and the opposite extremity 75 in engagement with the adjacent end of the section 23, the spring 25 acting to hold the sections 23 and 24 normally distended. Journaled in the outer ends of the arms 22 are the extremities of a vertical shaft 26 and 80 rotatably mounted upon the shaft 26 and insulated therefrom and from each other are axially alining rollers 27, the adjacent ends of the rollers 27 being separated by an insulating disk 28. The rollers 27 are formed 85 of material capable of conducting an electric current and connected to the respective rollers through the medium of rings and brushes are the terminals of conductors 29, while the remaining terminals of the conductors 29 are connected with the respective contacts 21 on the arm 20.

30 designates a double pole double throw switch and leading from the contact jaws at one side of the switch are conductors 31 100 terminally connected with the respective contacts of the pair 18, while leading from the contact jaws at the other side of the switch 30 are conductors 32 terminally connected with the respective contacts of the 105 pair 19, and connected with the blade of the switch 30 are the respective terminals of a suitable source of electrical energy, such, for instance, as a battery 33. The switch 30 may be either manually operated or under the 110 control of a road signal.

The car carried mechanism employed in

conjunction with my improved track obstacle may be of any suitable or preferred construction and embodies an electric motor 3 and a pair of contact strips 10 suitably secured to the locomotive connected with the respective terminals of the motor 3 by means of conductors 11. Located in the conductors 11 is a double pole single throw switch 12 whereby the connections between the contact strips and the motor may be made and broken. The motor 3 is connected through suitable mechanism with a controlling element of the propelling power of the motor car and with the brake valve so that when the motor is energized the propelling power of the car will be cut off and the brakes applied.

In practice, assuming the switch 30 to be manually controlled and located in a road station and assuming that the station agent wishes to bring a train, moving in one direction, to a standstill, the blades of the switch 30 are thrown into engagement with the jaws of the switch connected with the particular set of contacts 18 or 19, thereby effecting a connection between the storage battery 33 and the particular set of contacts. As the train runs by a track instrument, the contact strips 10 engage and ride over the rollers 27 respectively and when the rollers 27 are initially engaged by the contact strips 10, the post 17 is revolved under the action of the moving car and the contacts 21 on the arm 20 engage the particular pair 35 of contacts 18 or 19, depending upon the direction of travel of the train, thereby connecting the motor 3 on the train with the battery 33 so that the motor will be energized to operate the cut off device and brake valve. Thus, the train will be automatically stopped. By means of the telescopic arms 22 and the springs 25 therein the sections of the arms are permitted to move relatively to one another when the rollers are engaged 40 by the contact strips 10 and the springs act to hold the rollers 27 into engagement with the strips 10 under pressure, thereby insuring good electrical contact between the parts. Springs 34 are connected with the 45 post 17 at diametrically opposite points and act to maintain the post in normal position, that is, in a position to hold the arm 20 normally between the pairs of contacts 19 and restore the same to such position succeeding the release of the contact rollers by the strips 10. It will, of course, be understood that the strips 10 carried by the locomotive will be of such length as to insure the closing of the circuit of the motor 3 for 50 a sufficient length of time to operate the car carried stopping mechanism.

While I have herein shown and described the preferred form of my invention by way of illustration, I wish it to be understood 55 that I do not limit or confine myself to the

precise details of construction herein described and delineated, as modification and variation may be made within the scope of the claims without departing from the spirit of the invention.

70

I claim:

1. In train stopping apparatus, a track obstacle comprising a vertical post capable of rotary movement, elastic means holding said post normally stationary, pairs of contacts disposed at the opposite sides of said post, contacts carried by said post and movable into engagement with either pair of said first contacts according to the direction of movement of the post, contact rollers carried by said post and connected with the contacts thereon respectively, and a source of energy connected in circuit with said first-mentioned contacts.

75

2. In train stopping apparatus, a track 85 obstacle comprising a vertical post capable of rotary movement, elastic means holding said post normally stationary, pairs of contacts disposed at the opposite sides of said post, contacts carried by said post and movable into engagement with either pair of said first contacts according to the direction of movement of the post, contact rollers carried by said post and connected with the contacts thereon respectively, a source of 95 energy, and means for connecting said source of energy with either pair of the first-mentioned contacts.

90

3. In train stopping apparatus, a track 100 obstacle comprising a vertical post capable of rotary movement, means holding said post normally stationary, pairs of contacts disposed at the opposite sides of said post, contacts carried by said post and movable into engagement with either pair of said 105 first contacts according to the direction of movement of said post, arms carried by said post and spaced apart vertically and formed of relatively movable sections, contact rollers carried by said arms and insulated from each other and connected with the respective contacts on said post, and a source of energy connected in circuit with said first contacts.

110

4. In train stopping apparatus, a track 115 obstacle comprising a vertical post capable of rotary movement, means holding said post normally stationary, pairs of contacts disposed at the opposite sides of said post, contacts carried by said post and movable 120 into engagement with either pair of said first contacts according to the direction of movement of said post, arms carried by said post and spaced apart vertically and formed of relatively movable sections, contact rollers carried by said arms and insulated from each other and connected with the respective contacts on said post, a source of energy connected in circuit with said first contacts, and means acting upon the sections of said 125

130

arms to hold said sections normally distended.

5. In train stopping apparatus, a track obstacle comprising contact rollers insulated from each other, means carrying said rollers and capable of rotary movement, a source of electrical energy, means operable in the rotary movement of the first-mentioned means to connect said rollers with said

10 source of electrical energy.

6. In train stopping apparatus, a track obstacle comprising contact rollers insulated from each other, means carrying said rollers and capable of rotary movement, a source

of electrical energy, means operable in the 15 rotary movement of the first-mentioned means to connect said rollers with said source of electrical energy, and manually operable means controlling the connection between said source of energy and rollers 20 independently of the second-named means.

In testimony whereof I affix my signature in presence of two witnesses.

CHARLEY HIPP MAN.
